(57) **CLAIM**

I claim the ornamental design for a bottle opener, as shown and described.

DESCRIPTION

FIG. 1 is a side elevation view of the bottle opener showing my design, an opposite side view being a mirror image thereof.

FIG. 2 is a back view thereof;

FIG. 3 a front view thereof;

FIG. 4 is a bottom view thereof;

FIG. 5 is a top plan view thereof;

FIG. 6 is an upper perspective view thereof;

FIG. 7 is a rear perspective view thereof; and,

FIG. 8 is another rear perspective view thereof in the releasing position.
